CONTINUOUS FILM PRINTING MACHINE

Alan E. Freedman and August Zimmermann, New York, N. Y., assignors to De Luxe Laboratories, Inc., New York, N. Y.

Application January 25, 1932, Serial No. 588,670

16 Claims. (Cl. 95—75)

This invention relates to continuous film printing machines as may be used in printing a positive film from negatives, or more specifically, to improvements in printing machines permitting the printing of a positive film simultaneously from separate sound and picture negatives in either a forward or a reverse sense and for the printing of full frame pictures.

In the production of sound moving pictures, the sound accompanying the scene may be recorded on the same film from a composite negative from which the positive may be printed in the usual way using separate picture and sound printing lights. However, this method has many disadvantages. Greater flexibility, and more accurate results can be obtained by recording the sound and photographing the picture on separate films. Printing the positive was then accomplished by running the positive stock through a printer with the sound negative and then through another printer with the picture negative which necessarily involved double the time and labor in producing a positive film.

It is, therefore, an object of this invention to provide a continuous printer, compact in structure, that will print a positive film from separate sound and picture negatives passing through the printer in either a forward or reverse sense. After passing through the printer in one sense, the sound and picture negative, in this instance, can be removed from the take-up position and placed into the feed positions ready for a second run without rewinding and in which case the negative film travel will be in the reverse sense.

A further object of this invention is to provide a printer that is capable in addition to the printing of a positive film simultaneously from separate sound and picture negatives, of printing a positive film from a full frame picture negative.

It is also an object of this invention to provide visual means for indicating the sense of film travel in the printing of sound and pictures or the printing only of full frame pictures.

Other objects and advantages relate to details of the printer structure, the arrangement and relation of the parts thereof, all as will be apparent from the following description, taken in connection with the accompanying drawings in which:

Figure 1 is an elevation view of an embodiment of our invention.

Figure 2 is a plan view of the printer shown in Figure 1.

Figures 3 is a sectional view taken through line 3—3 of Figure 2.

Figure 4 is an enlarged elevation view showing the film feed apparatus, printing aperture and film positions for printing the picture portion of a film.

Figure 5 is an enlarged elevation view showing the film feed and printing apparatus and the film positions for printing the sound record portion of a film.

Figure 6 is a sectional view taken through line 6—6 of Figure 4.

Figure 7 is a sectional view taken through line 7—7 of Figure 9.

Figure 8 is a sectional view taken through line 8—8 of Figure 7.

Figure 9 is a sectional view taken through line 9—9 of Figure 7.

Figure 10 is a sectional view taken through line 10—10 of Figure 9.

Figure 11 is a sectional view taken through line 11—11 of Figure 5.

Figure 12 is a sectional view taken through line 12—12 of Figure 11.

Figure 13 is a sectional view taken through line 13—13 of Figure 12.

Figure 14 is a sectional view taken through line 14—14 of Figure 2.

Figure 15 is a sectional view taken through line 15—15 of Figure 14.

Figure 16 is an elevation view of the control assembly.

Figure 17 is a sectional view taken through line 17—17 of Figure 16.

Figure 18 is a longitudinal section view of the signal box taken through line 18—18 of Figure 1.

Figure 19 is a transverse section view of the signal box through line 19—19 of Figure 1.

Figure 20 is a plan view partly in section, of the electrical switching apparatus, as viewed in the plane of line 20—20 of Figure 4.

Figure 21 is a sectional view taken through line 21—21 of Figure 20.

Figure 22 is a sectional view taken through line 22—22 of Figure 21.

Figure 23 is a diagrammatic view of the electrical switching circuit.

In the drawings, like characters of reference will be used to indicate like parts.

In Figure 1, 1 designates a pedestal upon which the printing machine is mounted. On top of pedestal 1 is positioned a lamp chamber 2 for housing a printing light 3. In the forward extension 4 of the framework secured to chamber 2, is a cylindrical chamber designated at 5, preferably bored horizontally in a forward and rearward

direction and communicating radially with chamber 2 by means of a passageway 6.

Opposite passageway 6 in chamber 5 is located the picture printing aperture 7 formed by a circumferential channel cut through the wall of framework 4, as shown at 11 in Figures 4 and 7. A film drive sprocket comprising two axially spaced peripherally toothed wheels 9 mounted on a spindle 10, is co-axially disposed within chamber 10 5 and axially aligned so that the space between wheels 9 is in registration with aperture 7 and passageway 6. The channel at 11 is made slightly wider than the width of the positive and negative films so as to allow the same to pass over the bottom thereof and assume the curvature of wheels 9 while passing aperture 7.

The film guide plates 12 on either side of aperture 7 are placed tangentially to sprocket wheels 9 in the bottom of channel 11 to guide the films 20 properly to the driving sprocket. The width of aperture 7 is determined, in this instance, by means of two shutter members 8.

As previously pointed out in the objects of this invention, the printer is adapted to handle negative films passing in front of the printing apertures in either sense; that is to say, forwardly from beginning to end or in the reverse sense from the end to the beginning. The sense of movement of the negative will then determine near 30 which edge of the film the sound record is located.

In printing the picture portion, the sound record portion must be masked from the picture printing light in order to prevent fogging. However, since the printer is adapted to handle films 35 in either sense, the sound record portion will shift from one side to the other in accordance with the sense of negative film movement, making it necessary to provide a mask adjacent the inner edge of each sprocket wheel 9, only one of which will be 40 effective at a time. This mask arrangement and its operating mechanism is shown in Figures 6 to 10.

Upper shutter member 8 may be provided with downwardly projecting flanges 37, as shown in 45 Figure 8, each of which has a narrow and comparatively deep channel 45 adapted to receive sliding bars 38 and 39. On the lower ends of these bars and integral therewith, are located respectively, masking members 40 and 41, the widths of 50 which in a direction parallel to the spindle 10 are substantially equal to the width of the sound track portion of the film. The ends of masks 40 and 41 are shaped to conform with the cross section of aperture 7 between shutter members 8 at the 55 periphery of sprocket wheels 9 so that as either mask is in operative position, that particular portion of the aperture will be completely blocked against the passage of the printing light.

The lower sides of bars 38 and 39 are provided 60 with two spaced notches 42 and 43 adapted to engage successively, spring-pressed dog 44 pivoted in channel 45 by means of a pin 46 whereby the masks are held in either the lowered or raised position. Obviously, to accomplish the desired 65 result, mask 40 must be down when mask 41 is up, or vice versa.

In order to provide a simple shifting mechanism for these members, bars 38 and 39 have been extended through openings in the upper wall of frame 4 and are provided with hooked ends so as to engage a clevis 47 pinned to sliding members 48. Sliding members 48 may be operatively mounted in a guide member 49 secured to frame 4, as shown in Figure 10.

Transversely to sliding members 48 and directly

above, operatively positioned in a recess in guard member 49 is located a shifting plate 50, in this instance provided with a V-shaped perforation 51. On the upper surface of slide members 48 near the clevis connected end is secured, by means of a pin 52, a small roller 53 adapted to operate along the inner edges of the V-shaped perforation 51.

From Figure 9, it is apparent that when shifting plate 50 in the position shown by the full lines, or position A, one roller 53 will be located in the apex of perforation 51 while the other will be at the extremity of one leg thereof. In this position of shifting plate 50, mask 41 will be down or in a position to properly mask aperture 7 and mask 40 will be in the raised position. Now, if it is desired to reverse the positions of masks 40 and 41, shifting plate 50 is moved to the dotted position B and consequently the roller associated with bar 38 will carry mask 40 down and the roller associated with bar 39 will bring mask 41 up. Perforation 51 may be extended parallel to the direction of movement of plate 50, as shown at 54, so that plate 50 may be withdrawn farther than the full line position, or to position C, thereby allowing mask 40 to remain 25 in the raised position and also raising mask 41 adapting aperture 7 for the printing of a positive from a picture negative not provided with a sound track portion.

A cover plate 55 is provided to maintain shifting plate 50 in position and also to protect the shifting mechanism from dust and other foreign matter. The usual aperture gate 13 having its inner surface concaved to conform with the curvature of the film passing over sprocket wheels 9 is provided to maintain the films in proper engagement with the sprocket teeth. Aperture gate 13 is preferably mounted on arm 14 which is free to pivot at 15 so as to permit it to swing away from aperture 7 to allow the threading of the film over 40 sprocket wheels 9.

Positioned above chamber 2 is a second lamp chamber 16 housing a printing light 17 for printing the sound record from a separate sound negative. Opposite lamp 17 in the side of chamber 45 16 is an opening 18 communicating with a tapered tubular connecting member 19 which terminates at casing 20. Member 19 and casing 20 may be joined, as shown, by means of a threaded nipple 21. Casing 20 at its opposite end may be provided with a cylindrical chamber 22, the ends of 50 which are closed by flanged sprocket wheels 23 in co-axial relation therewith and axially spaced on a spindle 24 as shown in Figures 11 and 12.

The outside diameter of the cylindrical portion 55 of casing 20 is made substantially equal to the base diameter of sprocket wheels 23 in order to provide nearly frictionless movement of the films over the casing. Two narrow radial printing apertures 25 and 26 are provided in wall 27 adjacent the inner edge of sprocket wheels 23. Wall 27 is effective in masking the picture portion of the positive as the positive film and the negative sound film move over sprocket wheels 23 past apertures 25 and 26. The fact that two apertures 60 are here provided, will permit the printing of a sound negative passing the apertures in either a forward or a reversed sense.

It is, of course, to be understood that the sense of movement of the sound negative will determine 70 near which edge of the film the sound record is located. A reversal of sense will shift the record to the opposite edge. It is, therefore, necessary to provide a shifting mask for closing one of the sound printing apertures during the printing proc- 75

ess. For this purpose, mask 28 is provided in the form of a concentric semi-cylindrical member having overturned edges to slidably engage a tongue and groove arrangement along the edges 5 of wall 27.

Mask 28 may be shifted from side to side, as shown in the dotted positions of Figure 11, by means of an actuating lever 29 extending through a slot opening in the lower portion of casing 20 and pivoted at this point by a screw 30. A bracket 31 centrally secured to mask 28 and provided with a clevis and pin arrangement 32, serves as a coupling means between the mask and actuating lever 29.

It is self-evident from the drawings that the bent configuration of lever 29 within chamber 22 is necessary to clear sprocket wheel spindle 24. The externally projecting end of lever 29 may be pivoted through the medium of a spring toggle arrangement to shifting arm 33 adapted to be shifted from side to side.

It will be noted that lever 29 is pivoted by means of a thumb screw 34 to a slidably internally mounted block 35. Coil spring 36 applies a force 25 against lever 29 in line therewith, as long as the latter is in the central position, as shown in Figure 11. Now, as soon as shifting arm 33 is moved to either side, lever 29 will be forced out of its central position and urged by the action of spring 36 to the limit of its movement as determined by the sidewise limit of movement of mask 28.

The end of arm 29 may be slotted at its pivotal point with screw 34 so that arms 29 and 33 may be quickly dis-engaged by forcing screw 34 against the tension of spring 36 until the body of the screw clears the end of the lever. Shifting arm 33, in this instance, may be secured to shifting plate 50, as shown in Figure 9, so as to effect the simultaneous shifting of masks 40 and 41 with that of mask 28. A sound aperture gate 58 is provided for maintaining the negative sound film and the positive in close contact with sprocket wheel 23.

Aperture gate 58 may be resiliently mounted on a fogging head 59, as shown, the latter being provided with chambers 60 and 61 in which are housed fogging lights 62 and 63 respectively. Aperture gate 58 is provided with two passages 64 and 65 respectively, in alignment with apertures 26 and 25. Passages 64 and 65 are connected by passages 66 and 67 with light chambers 60 and 61.

It is now clear that the positive sound track portion may be fogged by the energization of either lamps 62 or 63 as conditions demand, for the purpose of obviating a certain portion of the sound record.

Lamps 62 and 63 may be controlled in any well-known way as, for instance, by a switch as shown at 68 actuated by a notch placed in the edge of the negative sound film. The selection of the proper lamp so as to fog the proper portion of the positive, may be accomplished by the use of a selector switch 160 having a switch-actuating arm 161 which may be associated with shifting arm 33 whereby the selection of the proper masks for both sound and picture will also make the proper fogging lamp circuit connection.

Fogging head 59 may be provided with light passages 69 leading from the light chambers 60 and 61 to the exterior and which may be covered with colored glass so as to give the operator an indication that the fogging lamps are in operative condition. The printing light for the sound film is preferably diffused by a diffusing plate 70 placed

in passageway 18. Adjacent plate 70 and secured to coupling member 19 is provided a shutter mechanism controlling the quantity of printing light comprising two movable shutter members 71 and 72 positioned in guide channels 74 and 75 and threaded upon an adjusting screw 73. Adjusting screw 73 may be provided with a right-handed screw thread for shutter 71 and a left-handed thread for shutter 72 whereby the distance between shutter members may be adjusted by turning screw 73 in either direction as desired.

In order to equalize the quantity of light falling on apertures 25 and 26, an auxiliary shutter member 76 is provided within casing 20 pivoted in the center on an inwardly projecting boss 77. The right hand side of shutter 76, as shown in Figure 13, has an inclined surface 78. A spring 80 secured to the upper wall 81 at one end and to shutter 76 at the other, rotates the shutter so that portion 78 is in contact with the beveled point 20 of an adjusting screw 79.

By adjusting the screw 79 in or out, shutter 76 will be rocked about its pivot so as to balance the light directed toward the respective apertures 25 and 26.

The above description has dealt generally and specifically with the apparatus units for exposing the positive film to both the picture and sound negatives. The arrangements of these units with respect to each other and the associated apparatus, as film feed and guide equipment is of great importance. In order to provide a compact structure, the picture printing is operated in one plane and the sound printing is accomplished in an adjacent plane.

Since all views showing the relative positions of the apparatus units are similar with respect to arrangement, we can simply designate these two planes as the near and the far plane. Secured to pedestal 1 and frame member 4 is, in this instance, a tubular framework 82 upon which are mounted the reel flanges and reel spindles for holding the feed and take-up reels of the positive stock and the picture and the sound negatives.

On the upper cross frame member 82 is mounted in the far plane, stock reel flange 83 and the picture negative reel flange 84. In the near plane is the reel flange 85 for the sound negative. On the vertical frame member 82 in the near plane is mounted the take-up stock reel flange 86. On the lower horizontal frame member 82 is mounted in the near plane the sound negative take-up reel flange 87, and on the same member in the far plane, the picture negative take-up flange 88. The reel flanges are all provided with reel spindles and reel guards of well-known construction and need no further explanation.

The various feed and take-up sprockets, as well as the take-up reels are driven by a train of gears located within gear case 89 mounted, as shown, on frame 4. In Figure 3, 90 is the main driving gear mounted on shaft 91 which extends through both sides of gear case 89 having mounted on the rear side a driving pulley 92 which may be connected by a belt 129 to pulley 130 of a driving motor 131 mounted on a bracket 132 secured to the side of frame 2.

On the front side of the gear case in the far plane, is mounted on shaft 91 a pull sprocket 93 for feeding out the positive stock and the negative picture film, and in the near plane is positioned a feed sprocket 23 which is the sound picture exposure sprocket. In mesh with gear 90 is an idler gear 94 which meshes with gear 95 mounted

on shaft 96 extending to the front side of gear case 89 and having mounted thereon in the near plane a pull sprocket 97 for feeding out the negative sound film. A second idler gear 98 is provided meshing with main driving gear 99 and gear 99 mounted on sprocket shaft 10 to which are secured sprocket wheels 9. Meshing with gear 99 is a smaller gear 100 mounted on shaft 101 extending to the rear of casing 89 and having mounted thereon the take-up reel driving pulley 102.

Gear 103 is in mesh with gear 100 and is, in turn, mounted on shaft 104 extending to the front side of gear case 89 through the far plane and into the near plane and upon which is mounted in the far plane, take-up sprocket 113 and in the near plane, take-up sprocket 105 for driving respectively the positive film and the sound and picture negatives to their respective destinations to be hereafter explained.

The printing of the positive picture portion from a negative picture film, is illustrated in Figure 4. This printing process takes place in the far plane. A positive film 106 and the picture negative 107 are placed in overlying relation and feed from their respective reels from positions 83 and 84 through guide rollers 108, 109 and 110 over pull sprocket 93. The films now pass separately through suitable tensioning devices indicated at 111 to guide rollers 112 onto driving sprocket 9 past the exposure aperture 7 and through take-up sprocket 113. The negative picture film 107 passes over guide roller 114 onto its take-up reel at 63. The positive film 106, however, upon leaving guide roller 114 moves over from the far plane to the near plane and travels upward to guide roller 115 located on fogging head 59 where it picks up the negative sound film 116, as shown in Figure 5.

Negative sound film 116 is fed from its reel at 85 to pull sprocket 97 aided by guide rollers 117 and 118 from which it passes onto the sound exposure sprocket 23. The positive film 106, after passing guide rollers 119 and 120 on fogging head 59, joins the negative sound film 116 and the two pass in overlying relation over sprocket 23 and are exposed by the sound printing light through either apertures 25 or 26. Films 106 and 116 then continue over guide rollers 121 to tensioning devices 122 onto take-up sprocket 105 guided by rollers 123 and 124, and then to their respective take-up reels at 86 and 87.

The take-up reels may be driven from pulley 102 by means of a belt 125 passing over the respective reel pulleys 126, 127 and 128. Thus it is seen that the printing of a positive film from separate sound and picture negatives is accomplished in one continuous operation through the printing machine. The negative sound and picture films on the wind-up reels, after passing through the printer, are immediately ready for the next run with a new positive film and may be placed in the feed positions without rewinding.

The sound track portion will, of course, be reversed, but this condition is met in the printer, as previously described, by providing sliding masks so that the negative films may be run through in either sense.

In order to give the operator of the printer an indication of the sense of film travel, a signal box 162 is mounted on lamp chamber 2. The face of the signal box may be provided with three words or other suitable indicia symbolical of the printing operation as, for instance, the upper signal 75 consists of the word "Forward" indicating that

the negative films are traveling through the printer in the forward sense. The next word may be "Backward" indicating that the negative films are moving through the printer in a reverse sense and the lower signal may be "Disc" or some similar indication meaning that the sound printing is discontinued and that a full picture frame film is being printed.

Details of signal box 162 are shown in Figures 18 and 19. A face plate 163 is provided having three elongated apertures through which the signal indications above-mentioned are made visible. A ruby-colored glass plate 164 may be positioned adjacent face plate 163 to prevent the emanation of any light rays other than red. Signal letters may be stenciled in a suitable metal plate 165 which is positioned directly in rear of glass plate 164 so as to have each signal word or symbol in alignment with its respective aperture in the face plate.

The interior of signal box 162 is divided into three compartments by longitudinally extending partition walls 166 and 167. Each compartment is provided with a signal lamp, as indicated at 169, 170 and 171, mounted in a suitable socket 168. Indicating lamps 169, 170 and 171 are controlled by switch 57 actuated by an actuating arm 56 secured to shifting arm 33 by means of a connecting link 172.

Switch 57 comprises contacts 173, 174 and 175 mounted on a suitable insulating block 176 and which may be respectively connected to lamps 169, 170 and 171. Contact fingers 177, 178 and 179, insulatingly mounted at one end as shown, to the frame of switch 57, are adapted to make contact respectively with, but are normally out of contact with contacts 173, 174 and 175. These contact fingers may be stamped from a single piece of spring metal so as to provide a connecting base integral therewith which may be connected to a suitable source of potential for lighting the signal lamps.

Lamps 169, 170 and 171 may have a common return circuit to a source of energizing potential. The successive engagement of the control fingers with their respective contacts, is accomplished by plungers 180 extending through the wall of switch casing 57 and have an insulated head 181 contacting with each contact finger. The portion of plunger 180 extending to the exterior of switch casing 57 is adapted to engage a cam surface 182 provided on switch lever 56, the latter being pivoted at one end to the switch casing as shown at 183. Now, as the shifting arm 33 is moved in order to place shifting plate 50 into one of the three positions, say position A, switch arm 56 connected to arm 33 will be rotated about pivot 183 and cause surface 182 to engage with plunger 180 which is pressed inwardly against contact finger 178 which, in turn, engages contact 174 to close the circuit to energize signal lamp 170. Consequently, the shifting of arm 33 into positions B and C will respectively close the circuits to respectively energize lamps 169 and 171.

As previously pointed out, the selection of the proper fogging light for obviating desired portions of the sound record, is accomplished simultaneously with the shifting of arm 33 to which is connected actuating arm 161 of selector switch 160. The wiring diagram of signal lamps 169, 170 and 171 and fogging lamps 62 and 63 is shown in Figure 23 for the masks in position A.

Wires 184 and 185 may be connected to a suitable source of potential for energizing the signal

lamps, as well as the fogging lamps. In position A, current will flow from the source through wire 185, contact 174, lamp 170 and return through wire 184.

5 The energization of lamp 170 indicates in signal box 162 that the masks in the sound and picture printing apertures are set for the negative films to pass through the printer in the backward sense. At the same time, selector switch 10 160 will be in position to make the energization 15 of fogging lamp 62 possible. Lamp 62, of course, will not be energized until switch 68 is closed by the action of a notch placed in a predetermined 20 position along the edge of the sound negative. Similarly, in position B, signal lamp 169 will be energized and fogging lamp 63 will be connected in circuit.

25 The energization of signal lamp 169 will give a visual signal in the signal box that the masks 30 are set for the negative films to pass through the printer in a forward sense. In like manner in position C, all connections to fogging lamps 62 and 63 are broken and signal lamp 171 is energized, indicating that the masks are in a 25 position to print a positive film from a full picture frame negative.

30 The printing machine is put into operation by means of a control lever 133 secured to the end of control shaft 134 journaled in bearing 136 located in a projecting portion of pedestal 1.

35 On the opposite end of control shaft 134 is secured a crank arm 135. Journaled to crank arm 13 by means of a crank pin 137, are control rods 138 and 193, the former connecting with arm 140 pivoted on spindle 142 secured to bracket 144 mounted on motor support bracket 132. Arm 140 is provided with a belt-tightening idler pulley 141 adapted to engage belt 129 as arm 140 is urged downward due to a counterclockwise rotation 40 of control shaft 134.

45 A stationary idler pulley 143 may also be used on spindle 142 to provide more belt contact surface on motor pulley 130. Thus it is seen that the mechanical mechanism is put into motion by tightening driving belt 129 which transmits the motion of motor 131 to driving pulley 92.

50 Uniform motion may be secured of all sprockets by means of a fly wheel 145 mounted on shaft 91 adjacent driving pulley 92. The inertia of fly wheel 145, however, will cause the sprockets to continue to rotate after the driving motor 131 is uncoupled by loosening belt 129.

55 In order to bring the mechanism to rest quickly, a breaking mechanism is provided comprising a brake shoe 146 acting on the rim of fly wheel 145 and actuated by means of a brake lever 147 pivoted intermediate its ends at 148 to gear case 89. One end of brake lever 147 may be secured to brake shoe 146 and the other end connected to 60 control rod 139. Rod 139 may be provided with a spring-tensioning device 149 effective in thrust as control lever 133 is turned to the off position releasing the driving belt tension and, at the same time, forcing brake shoe 146 against the 65 rim of fly wheel 145.

70 Rod 138 may also be provided with a certain amount of flexibility by spring-tensioning arrangement, as shown at 150, Figures 3, 14 and 15 which becomes effective in tension. The structures 149 and 150 being well-known, need no further explanation.

75 Support bearing 136 may be provided with stops 151 and 152 for limiting the movement of control shaft 134. A coil spring 153 suspended from crank pin 137 to an anchoring stud 154

maintains, by virtue of the anchoring stud's position, control lever 133 in either the "on" or "off" position.

Another feature in connection with the control system is the lock-out mechanism controlled by 5 the position of the sound and picture aperture gates 52 and 13 respectively.

As previously described, sound aperture gate 58 is mounted on fogging head 59 which, in turn, is hinged to lever 155 and pivoted to gear case 89 10 so that it is free to swing toward and away from sprocket 23 which enables the positive and the negative sound films to be threaded into place. The picture aperture gate is similarly constructed, as previously pointed out. 15

Starting the printing operation with either aperture gate open, would very likely destroy the films. Then, in order to prevent the starting of the machine until both gates are closed, a lock-out system is provided which comprises a connecting rod 156 connecting fogging head 59 and arm 15, and a second rod 157 leading from arm 15 to control shaft 134. The lower end of rod 157 is supported in a radial guide 158 secured to bearing 136 and is provided with a bayonet point 25 adapted to fit into a detent 159 located in control shaft 134.

30 Detent 159 is positioned so that rod 157 is in registration therewith as control lever 133 is in the "off" position. Under these conditions, rod 35 157 is free to move downwardly also allowing rod 156 downward movement thereby permitting aperture gates 13 and 58 to be withdrawn. It is, therefore, readily seen that when either or both aperture gates are open, rod 157 will lock control 35 shaft 134 in the "off" position.

35 This construction also prevents aperture gates 13 and 58 from being open while the machine is in motion since in the "on" position of lever 133, detent 159 is rotated out of registration with the 40 end of rod 157, as shown in the dotted position of Figure 17.

45 Although we have shown and described a particular embodiment of our invention as being illustrative thereof, we do not wish to limit ourselves to details of the precise structure shown or to the arrangement of the various parts thereof, as many changes and modifications may be made without departing from the spirit and scope 50 of the appended claims.

We claim:

1. A continuous film printing machine comprising 55 a base, a frame including a cylindrical portion having a circumferentially positioned exposure aperture therein, a picture exposure sprocket comprising peripherally toothed wheels axially spaced the width of said aperture and co-axially mounted within said cylindrical frame portion, means for moving a negative film having a picture 60 record thereon and a positive in overlying relation over said exposure sprocket, means for exposing said film through said aperture, means for alternately masking a portion of said aperture adjacent the inner edge of said sprocket wheels, a cylindrical open end casing having two circumferentially positioned exposure apertures extending 65 from said frame, a sound exposure sprocket comprising peripherally toothed wheels axially spaced and positioned co-axially in the ends of said casing, means for moving a negative film having a sound record thereon and said positive film in overlying relation over said sprocket, means for exposing said last-named films through either 70 one of said apertures, means for masking either of said apertures and means for simultaneously 75

- controlling said picture aperture and said sound aperture-masking means.
2. A continuous film printing machine comprising a base, a frame including a cylindrical portion having a circumferentially positioned exposure aperture therein, a picture exposure sprocket comprising peripherally toothed wheels axially spaced the width of said aperture and co-axially mounted within said cylindrical frame portion, means for moving a negative film having a picture record thereon and a positive in overlying relation over said exposure sprocket, means for exposing said film through said aperture, means for alternately masking a portion of said aperture adjacent the inner edge of said sprocket wheels, a cylindrical open end casing having two circumferentially positioned exposure apertures extending from said frame, a sound exposure sprocket comprising peripherally toothed wheels axially spaced and positioned co-axially in the ends of said casing, means for moving a negative film having a sound record thereon and said positive film in overlying relation over said sprocket, means for exposing said last-named films through either one of said apertures, means for masking either of said apertures, and means for simultaneously controlling said picture and said sound aperture masking means.
3. In a continuous film printing machine having a picture exposure aperture past which a negative picture film and a positive film are adapted to move in overlying relation and two laterally spaced sound exposure apertures past which are subsequently adapted to move, a negative sound film and said positive film in overlying relation, means for alternately masking portions of said picture exposure aperture, means for alternately masking said sound exposure apertures, means for simultaneously controlling said sound and said picture aperture masking means, and means controlled by said last-named means for indicating the position of said masking means.
4. In a continuous film printing machine having a picture exposure aperture past which a negative picture film and a positive film are adapted to move in overlying relation and two laterally spaced sound exposure apertures past which are subsequently adapted to move, a negative sound film and said positive film in overlying relation, means for alternately masking a narrow portion adjacent either edge of said picture exposure aperture, means for alternately masking said sound exposure apertures, means for simultaneously controlling said sound and said picture aperture masking means, and means controlled by said last-named means for indicating the position of said masking means.
5. In a continuous film printing machine having a picture exposure aperture past which a negative picture film and a positive film are adapted to move in overlying relation and two laterally spaced sound exposure apertures past which are subsequently adapted to move, a negative sound film and said positive film in overlying relation, means for alternately masking a narrow portion adjacent either edge of said picture exposure aperture, means for alternately masking said sound exposure apertures, means for simultaneously controlling said sound and said picture aperture masking means, signal lamps for indicating said masking positions, and means actuated by said last-named means for controlling said signal lamps.
6. In a continuous film printing machine having a picture exposure aperture past which a neg-
- ative picture film and a positive film are adapted to move in overlying relation and two laterally spaced sound exposure apertures past which are subsequently adapted to move, a negative sound film and said positive film in overlying relation, means for masking a narrow portion adjacent either edge of said picture exposure aperture, means for masking said sound exposure apertures, control means for alternately actuating said picture aperture masking means and for rendering said picture aperture masking means ineffective, additional control means actuated simultaneously with said first-named control means for alternately actuating said sound aperture masking means, signal lamps for indicating said masking positions, and means actuated by said control means for controlling said signal lamps.
7. In a continuous film printing machine having a picture exposure aperture past which a negative picture film and a positive film are adapted to move in overlying relation and two laterally spaced sound exposure apertures past which are subsequently adapted to move, a negative sound film and said positive film in overlying relation, means for masking a narrow portion adjacent either edge of said picture exposure aperture, means for masking said sound exposure apertures, control means for alternately actuating said picture aperture masking means and for rendering said picture aperture masking means ineffective, additional control means actuated simultaneously with said first-named control means for alternately actuating said sound aperture masking means, signal lamps for indicating said masking positions, means actuated by said control means for controlling said signal lamps, means for alternately fogging portions of said positive film underlying said sound printing apertures, and means controlled by said mask actuating control means for rendering said fogging means inoperative for portions of said positive film underlying a masked sound printing aperture.
8. In a continuous film printing machine having a picture exposure aperture past which a negative picture film and a positive film are adapted to move in overlying relation and two laterally spaced sound exposure apertures past which are subsequently adapted to move, a negative sound film and said positive film in overlying relation, means for masking a narrow portion adjacent either edge of said picture exposure aperture, means for masking said sound exposure apertures, control means for alternately actuating said picture aperture masking means and for rendering said picture aperture masking means ineffective, and additional control means actuated simultaneously with said first-named control means for alternately actuating said sound aperture masking means.
9. In a continuous film printing machine, a picture exposure aperture past which a negative picture film and a positive film are adapted to move in overlying relation, two laterally spaced sound exposure apertures laterally offset with respect to said picture exposure aperture past which are subsequently adapted to move a negative sound film and said positive film in overlying relation, means for alternately masking portions of said picture exposure aperture, means for alternately masking said sound exposure apertures, and means for simultaneously controlling said sound and said picture aperture masking means.
10. In a continuous film printing machine, a

picture exposure aperture past which a negative picture film and a positive film are adapted to move in overlying relation, two laterally spaced sound exposure apertures laterally offset with respect to said picture exposure aperture past which are subsequently adapted to move a negative sound film and said positive film in overlying relation, means for alternately masking portions of said picture exposure aperture, means for alternately masking said sound exposure apertures, means for simultaneously controlling said sound and said picture aperture masking means, and means controlled by said last-named means for indicating the position of said masking means.

11. In a continuous film printing machine, means for printing a picture negative on to a positive film including a picture exposure aperture, means for subsequently printing a sound negative on to said positive film including two laterally spaced sound exposure apertures, said sound printing means being displaced laterally with respect to said picture printing means, means for shifting said positive film edgewise during the interval between printings, means for alternately masking portions of said picture exposure aperture, means for alternately masking said sound exposure apertures, and means for simultaneously controlling said picture and said sound masking means.

12. In a continuous film printing machine, means for printing a picture negative on to a positive film including a picture exposure aperture, means for subsequently printing a sound negative on to said positive film including two laterally spaced sound exposure apertures, said sound printing means being displaced laterally with respect to said picture printing means, means for shifting said positive film edgewise during the interval between printings, means for alternately masking portions of said picture exposure aperture, means for alternately masking said sound exposure apertures, means for simultaneously controlling said picture and said sound masking means, and means for indicating the position of said masking means.

13. In a continuous film printing machine, means for printing a picture negative on to a positive film including a picture exposure aperture, means for subsequently printing a sound negative on to said positive film including two laterally spaced sound exposure apertures, said sound printing means being displaced laterally with respect to said picture printing means, means for shifting said positive film edgewise during the interval between printings, a masking member positioned adjacent either side of said picture exposure aperture movable at will into and out of operative position, a sliding mechanism for controlling the position of said masking members, a sound aperture masking member slidably adapted to alternately cover said sound exposure apertures, an actuating lever therefor, and a mechanical linkage between said sliding mechanism and said actuating lever for simultaneously controlling the positions of said picture exposure masks and said sound exposure masks.

14. In a continuous film printing machine, means for printing a picture negative on to a positive film including a picture exposure aperture, means for subsequently printing a sound negative on to said positive film including two laterally spaced sound exposure apertures, said sound printing means being displaced laterally with respect to said picture printing means, means for shifting said positive film edgewise during the interval between printings, a masking member positioned adjacent either side of said picture exposure aperture movable at will into and out of operative position, a sliding mechanism for controlling the position of said masking members, a sound aperture masking member slidably adapted to alternately cover said sound exposure apertures, an actuating lever therefor, a mechanical linkage between said sliding mechanism and said actuating lever for simultaneously controlling the positions of said picture exposure masks and said sound exposure masks, and an electrically energized system including a switch controlled by said mechanical linkage for indicating the position of said masks.

15. In a continuous film printing machine having a picture exposure aperture past which a negative picture film and a positive film are adapted to move in overlying relation and two laterally spaced sound exposure apertures past which are subsequently adapted to move, a negative sound film and said positive film in overlying relation, a masking member positioned adjacent either side of said picture exposure aperture movable at will into and out of operative position, a sliding mechanism for controlling the position of said masking members, a sound aperture masking member slidably adapted to alternately cover said sound exposure apertures, an actuating lever therefor, and a mechanical linkage between said sliding mechanism and said actuating lever for simultaneously controlling the positions of said picture exposure masks and said sound exposure masks.

16. In a continuous film printing machine having a picture exposure aperture past which a negative picture film and a positive film are adapted to move in overlying relation and two laterally spaced sound exposure apertures past which are subsequently adapted to move, a negative sound film and said positive film in overlying relation, a masking member positioned adjacent either side of said picture exposure aperture movable at will into and out of operative position, a sliding mechanism for controlling the position of said masking members, a sound aperture masking member slidably adapted to alternately cover said sound exposure apertures, an actuating lever therefor, a mechanical linkage between said sliding mechanism and said actuating lever for simultaneously controlling the positions of said picture exposure masks and said sound exposure masks, and an electrically energized system including a switch controlled by said mechanical linkage for indicating the position of said masks.
